UNITED STATES PATENT OFFICE

GEORGE M. MAIER, OF PELHAM, NEW YORK, ASSIGNOR TO AMERICAN RADIATOR COMPANY, OF NEW YORK, N. Y., A CORPORATION OF NEW JERSEY

GAS VALVE

Application filed July 27, 1928. Serial No. 295,707.

My invention relates to improvements in means for controlling and regulating the passage of fluid through pipes and the like, and the same has for its object particularly to provide a valve which is simple in construction, efficient in operation, and inexpensive to manufacture.

Further, said invention has for its object to provide a valve for use in connection with apparatus employing gas as fuel, in which a pilot light or reduced flame is maintained when the fuel burner or flame is not in operation.

Further, said invention has for its object to provide a valve for use in connection with apparatus employing gas as fuel in which the volume and rate of flow of the gas may be duly controlled to supply a pilot light or a reduced flame when the main burner, or the entire burner, is not in operation.

Further, said invention has for its object to provide a valve controlling the supply of gas to a main burner and a pilot burner, and in which, when the valve is actuated, the gas will be permitted to pass through a secondary passage to the pilot burner before the supply of gas through the main passage leading to the main burner is completely opened, and vice versa.

Further, said invention has for its object to provide a valve which will prevent a large volume of gas suddenly entering the burner and issuing therefrom before the same can be ignited, and causing the combustion chamber to become suddenly flooded with gas which would result in an explosion when the gas is ignited.

Further, said invention has for its object to provide a valve in which the means for securing the operating handle to the valve stem also serves as a pointer to cooperate with the indicating means provided upon the valve body to indicate the several positions in which the valve may be adjusted.

Further, said invention has for its object to provide a valve in which the means for receiving the indicating means for showing the position of the valve stem which also serves as the means for limiting the movement of said valve stem and associated parts

is formed as a separate element and secured to the valve body.

Other objects will in part be obvious and in part be pointed out hereinafter.

To the attainment of the aforesaid objects and ends, my invention consists in the novel details of construction, and in the combination, connection and arrangement of parts hereinafter more fully described and then pointed out in the claims.

In the accompanying drawings—

Figure 1 is an end or side view showing one form of valve constructed according to, and embodying my said invention;

Fig. 2 is a face or top view thereof;

Fig. 3 is a similar view partly broken away and in section to show the passages thereof;

Fig. 4 is a cross section on the line 4—4 of Fig. 1 showing the valve in an intermediate position;

Fig. 5 is a detail section on the line 5—5 of Fig. 2, showing the construction of the combined handle securing and indicating means, and

Fig. 6 is a detail perspective view of the dial or indicating plate.

In said drawings, 10 designates a valve casing comprising a hollow body portion 11 of substantially cylindrical form having an inlet portion 12, and an outlet portion 13 extending radially from said body portion. The outlet portion 13 is provided upon its outer end with a hexagonal part 14, and with internal screw threads 15. The inlet portion 13 is provided on its outer side with an enlarged end having external screw threads 16. 17 denotes the valve proper or plug which is preferably of slightly tapering form and revolvably disposed within the body portion or valve casing 10, and is provided with a main outlet passage 18 corresponding in diameter to and adapted to register with the passages 12^a, 13^a of the outlet and inlet portions 12, 13, respectively of the valve cas-

ing, and a similar inlet passage 19, arranged at right angles to and communicating at its inner end with the inner end of the main outlet passage 18. The outer end of said passage 19 is also adapted to be brought into

register with the passage 13^a of the outlet 13. Diametrically opposite to the passage 19, the valve plug 17 is provided with a circular recess 17^a from the base of which extends a secondary outlet passage 18', of smaller diameter than the recess 17^a, communicating with the inner end of the outlet passage 18.

The forward end of the valve or plug 17 is provided with a spherical head 22 having a shallow socket 24 at its exposed end whose base is arranged at an angle of about twenty-five degrees (25°) to the longitudinal axis of the plug. The socket 24 is adapted to receive the reduced end of a handle 25. From the central part of said socket extends a small screw-threaded aperture 26 adapted to engage with the threaded intermediate portion 27 of a screw 28 which extends longitudinally through the handle 25, and serves to secure said handle to the valve or plug 17.

The extreme end 29 of the screw 28 is reduced in diameter and pointed, and projects downwardly from and out of the rear end of the head 22 of the valve 17. The projecting end 29 of said screw serves also as a pointer and works over an annular index or dial plate 30 secured by screws or pins 31 extending through said plate 30 at opposite sides thereof, into ears 32 extending radially from the outer sides of the valve casing 11 at its forward end.

The index or dial plate 30 is provided at suitable points upon its inner edge with upwardly extending ears or projections 33 which are preferably formed integrally with said plate and serve as stops adapted to engage with the projecting end 29 or pointer of the screw 28 whereby to limit the rotary movement of the valve or plug 17 in either direction, and to cause the several passages therein to register accurately with the passages in inlet and outlet portions 12, 13 of the valve.

The inlet portion 12 is provided with a lateral extension 35 having a small threaded opening 36 therein opening into a larger threaded recessed portion. 38 denotes a stem having an enlarged threaded intermediate part 39 engaging the threaded opening 36. The outer end of said stem 38 is provided with a slot 40 to receive the end of a tool for actuating said stem. 41 denotes a screw cap having a polygonal head 42. The threaded part 42 of said cap is adapted to engage with the threaded recessed portion 37, and the inner end of said threaded part is adapted to bear upon a washer 43 to form a tight seal between the inner portion of said extension 35 and said cap 41. The recess 44 in the under side of said cap 41 is of such depth as will permit of the outer slotted end of the stem 38 being completely retracted so as to leave the passage 12^a unrestricted in area for the passage of gas. By adjusting the stem 38 so that its inner end may extend to a greater or less extent into the passage 12^a, the area of

said passage 12^a may be varied to regulate or control the rate of flow of the gas through the passage and at the same time the pressure on the outlet side of the valve will be reduced to meet any given operating requirements or 70

When the apparatus employing a gas burner or burners to heat the same is not in operation, the supply of gas will be completely shut off by turning the handle 25 to the left, and 75 until the projecting end or pointer 29 of the screw 28 engages with the right-hand stop 33 on the index or dial plate 30 adjacent to the word "Off." When the handle 25 is adjusted to this position, the solid portion of the valve 80 or plug 17 will close the outlet passage 12^a of the valve casing.

If it is now desired to operate the apparatus, and supply gas to the burner, it merely becomes necessary to turn the handle 25 to the 85 right. When the handle reaches a vertical position the pointer 29 will register with the dial indication 34 associated with the word "Pilot" whereupon gas will pass through the reduced or secondary passage 18' communicating with the main outlet passage 18 and to the outlet 13^a of the valve casing, and thus permit a limited but uninterrupted amount of gas to pass to the burner. When the full supply of gas for operating the main burner is required, the movement of the handle 25 is continued to the right, and until the pointer 29 contacts with the left-hand stop 33 associated with the word "On," whereupon the full supply of gas will be permitted to pass from 90 the inlet passage 12^a to the burner through the inlet passage 19 and main outlet passage 18 to the outlet passages 13, 13^a of the casing. 95

In operating the valve to admit the full supply of gas to the burner, it is important 105 to prevent a large amount of gas suddenly entering the burner and passing into and filling the combustion chamber of the apparatus as this would be very likely to cause an explosion when the gas is ignited. To prevent such result only a small amount of gas is permitted to reach the burner before the full supply becomes available. This is accomplished by providing the valve or plug 17 with the recess 17^a which communicates with the reduced secondary outlet passage 18' communicating with the main outlet passage 18. Thus, when the valve or plug 17 is turned to the left, (the handle to the right), a small initial amount of gas is permitted to pass from the inlet passage 12, through the recess 17^a, and into the outlet passage 13^a, and as the movement of the valve plug 17 is continued and the recess 17^a brought into register with the outlet passage 13^a the open end of the passage 18 in the valve or plug 17 will be brought simultaneously into register with the inlet passage 12 of the valve casing and gas be permitted to pass to the outlet 13^a by way 110 of the reduced secondary outlet passage 18. 115

The limited supply of gas supplied by this channel will continue until the opening end of the main outlet passage 18 in the valve or plug comes into full register with the outlet passage 13^a at which time the further movement of the valve 17 will be arrested by the contact of the pointer 29 with the left hand stop 33 on the dial plate.

Having thus described my said invention, what I claim and desire to secure by Letters Patent is:

1. In a valve, a stem, a handle, and means for securing said handle to said stem; said securing means extending beyond said stem and serving as a pointer, substantially as specified.

2. In a valve the combination of a stem, with a handle, and means for securing said handle to said stem, a part of said securing means extending beyond said stem and serving as a pointer, substantially as specified.

3. In a valve, the combination of a stem with a handle, and means extending longitudinally through said handle, and through said stem for securing said handle to said stem; the portion of said securing means projecting beyond said stem serving as a pointer, substantially as specified.

4. In a valve the combination of a stem with a handle, a member extending longitudinally through said handle, a threaded intermediate portion on said member engaging said stem, and an end beyond said threaded portion projecting out of said stem and serving as a pointer, substantially as specified.

5. In a valve the combination of a stem having a socket at its exposed end, and a threaded opening extending from the base of said socket, with a handle having one end disposed within said socket, a member extending longitudinally through said handle, and a threaded portion on said member engaging the threaded opening in said stem; the rear end of said member projecting out of said stem and serving as a pointer, substantially as specified.

6. A valve of the character described comprising a casing having an inlet and an outlet, a valve revolvably disposed in said casing, means for actuating said valve, a pointer carried by said valve, an annular dial plate secured upon said casing and surrounding said valve, and means projecting from the inner edge of said dial plate for engagement with said pointer for limiting the movement of said valve, substantially as specified.

7. A valve of the character described comprising a casing having an inlet and an outlet, a valve revolvably disposed in said casing a handle secured to said valve for actuating the same, a pointer carried by said handle, an annular dial plate secured upon said casing, and ears struck up from said dial plate adjacent to its inner edge adapted for engage-

ment with said pointer for limiting the movement of said valve, substantially as specified.

8. A valve of the character described comprising a casing having an inlet and an outlet, a valve revolvably disposed in said casing, a handle secured to said valve for actuating the same, a pointer carried by said valve, an annular dial plate secured upon said casing, and ears struck up from the inner edge of said dial plate adapted for engagement with said pointer for limiting the movement and for indicating the several positions of said valve, substantially as specified.

9. In a valve, a stem, an operating element for said stem, and means for securing said operating element to said stem; said securing means extending beyond said stem and serving as a pointer, substantially as specified.

Signed at the city of New York, in the county and State of New York, this 6th day of July, one thousand nine hundred and twenty-eight.
